INTERNAL COMBUSTION ENGINE

Lionel M. Woolson, deceased, late of Detroit,
Mich., by Emma F. Woolson, executrix, Bloom-
field, Mich., assignor to Packard Motor Car
Company, Detroit, Mich., a corporation of
Michigan

Application November 13, 1931, Serial No. 574,792

14 Claims. (Cl. 123—140)

This invention relates to internal combustion engines and more particularly to mechanism for injecting fuel charges into engine cylinders.

One form of injection device for engines of the class mentioned includes a spring closed nozzle valve associated with an engine actuated push plunger, and consequently the atomization and the pressure at which the fuel charges are injected vary in accordance with the engine R. P. M. Ordinarily, injection devices of this character provide sufficient atomization and pressure of the fuel charges above an idling engine speed to insure a proper commingling with compressed air charges in the cylinders, but at idling engine and starting speeds the pump plungers move too slowly to exert the pressure required to properly atomize and project the fuel charges into the compressed air charges in the combustion chambers so that the necessary commingling results to insure combustion by compression of the mixture. As a consequence the engine is difficult to start and often stops during idling, and an object of this invention is to provide fuel injection means which will avoid these undesirable conditions.

Another object of the invention is to provide a pair of engine actuated injection devices for each cylinder of an engine which are actuated to operate one during the idling engine speeds and the other during the engine speeds above idling.

A further object of the invention is to provide a pair of engine driven fuel injection devices, for each cylinder of a compression-ignition engine, which are operable one at a time through automatically controlled mechanism so that a fuel pressure will be developed at any engine speed to project the fuel charges into compressed air charges sufficiently to obtain a fuel mixture which will result in combustion by compression.

These and other objects of the invention will appear from the following description taken in connection with the drawings, which form a part of this specification, and in which:

Fig. 1 is a rear end elevation, partly in section and partly broken away, of an engine having the invention associated therewith;

Fig. 2 is a sectional view of the same taken on line 2—2 of Fig. 1;

Fig. 3 is a sectional view of the nozzle portion of one of the injection devices associated with a fragment of a cylinder.

Referring now to the drawings by characters of reference, 10 represents the cylindrical crank case of a Diesel engine designed preferably to be utilized as the power plant of an airship. Cylinders

11 extend radially from the crank case and are formed with flanges 12 which bear against and are secured to the crank case by a pair of hoops 13 placed in an initial tension greater than that developed therein by engine developed forces. The crank case is provided with spaced reinforcing walls, one of which is indicated at 14, each of which extends in a plane with one of the hoops, while a wall 15 encloses the rear end of the crank case and with the rearmost wall 10 14 forms a compartment for mechanism to be hereinafter described.

The engine illustrated is of the four cycle type and each cylinder head is provided with a single Venturi passage 16 which serves as both the air inlet and exhaust outlet, there being an open end conduit 17 extending transversely of the outer end of each passage and in communication therewith. The passages extend at an angle to the axis of the associated cylinders and tangentially of the inner wall of the cylinders so that air drawn therethrough into the cylinders by the pistons, as indicated at 18, will be caused to move in a spiral direction. A valve 19 controls the interior end of each passage 16 and a plurality of springs 20 normally maintain each valve in closed position. The valves are open during the exhaust and intake strokes and for so actuating the valves, mechanism extends through the housings 21 and 22 and includes rods 23 which bear against rock levers 24 carried by shafts 25 in the crank case.

Charges of rotating air are compressed in the cylinders by the pistons, and during such compression a charge of atomized fuel oil is injected into the air by means of either one of pairs of devices indicated generally at 26 and 27. These devices are substantially similar in design and comprise generally a nozzle section and a pump section which are preferably secured together as an integral unit and secured to the cylinders by bolts 28, the nozzle sections of the devices 27 being longer so that the pump will be in a plane behind that of the devices 26. A nozzle section of one of the injection devices is illustrated in Fig. 3 and includes a barrel 29 having an end extending through an opening in the cylinder wall, there being a valve member 30 in the axially extending barrel passage having a head 31 lying within and cooperating with the tapered outlet end of the passage to determine the size of the circular opening. A coil spring 32 encircles the valve member in the barrel passage and is arranged to urge the valve in a direction away from the cylinder, a stop member 33 limiting such

movement in a manner to just prevent the valve head from striking the barrel.

- 5 A pump casing 34 is screwed upon each nozzle section and carries a barrel 35, there being a passage connecting the pump barrel with the axial nozzle passage and a one-way valve 36 arranged therein to prevent back flow. A plunger 37 is arranged in the barrel and controls the passage of fuel oil through the ports 38, and conduit sections 39 connect the housings 40 with which the ports communicate. A reservoir and low pressure pump (not shown) are associated with the fuel manifold which consists of the housings and conduits.
- 10 15 Mechanism is associated with each plunger for causing reciprocation thereof. A rod 41 is carried in a sleeve 42 extending through the crank case in alignment with each pump plunger, and there is an axially adjustable end 43 associated with 20 such rods which engages the aligned plunger. A coil spring 44 is arranged in each pump casing and exerts pressure urging the pump plunger toward the crank case. Another rod 45 pivotally engages the end of each rod within the crank case 25 and oppositely extending slippers or rock levers 46 and 46' are pivotally mounted side by side on each of the shafts 25 to receive the pairs of rods 45. It will be seen that the mechanisms for operating the injection devices 26 are in the same 30 vertical plane while the mechanisms for operating the injection devices 27 are in a similar plane but to the rear of the mechanism for actuating the devices 26. The slippers are provided with a curved face 47 upon which the rods 45 bear and the relation of the rods 45 longitudinally of the slippers determines the plunger timing and effective injection stroke. In order to vary the position of such rods, links 48 are pivotally associated therewith and are secured 40 upon pins 49 extending from the rotatable ring 50, the ring having a rack 51 with which the gear segment 52 on the shaft 53 meshes. Suitable mechanism is associated with the shaft to rotate the same from a point remote from the engine.
- 45 The crank shaft 54 extends axially through the crank case and a starter jaw extension 55 is splined to the rear end thereof and secured against endwise displacement by a bolt 55'. A cam 56 for actuating the valve actuating mechanism rods 23 telescopes the crank shaft and is axially retained thereon by the nut 57, and reduction gearing 58, 59, 60 and 61 is arranged to rotate the cam at $\frac{1}{2}$ crank shaft speed and in a counter clockwise direction viewed from the rear end. The cam 56 has a forwardly extending hub upon which a cam 61' is splined so that it will rotate therewith and can be shifted axially to a position for actuating either group of rocker levers of mechanisms for operating the devices 26 and 27. Spaced axially on the periphery of the cam 61' are two rows of lobes 61² and 61³, the lobes 61² being arranged to contact with the rocker levers 46' when the cam is in its rear position, and the lobes 61³ being arranged to contact with the rocker levers 46 when the cam is moved to its forward position. There are four lobes in each group and the cam is driven at $\frac{1}{2}$ crank speed so that each rocker lever, in the group with which the cam is associated, will be actuated once in each two revolutions of the crank shaft. A retainer plate 62 is secured to the front end of the hub of the cam 56 and a coil spring 63 extends intermediate the retainer plate and the cam 61' and thus urges the fuel cam toward its

rear position where it will actuate the injection devices 27.

Automatic mechanism is provided for shifting the cam 61' to a forward position where it will actuate the injection devices 26, and such mechanism is shifted by a governor responsive to the crank shaft rotation. To this end weight members 64 are pivoted at 65 to the crank shaft extension and are provided with arms 66 engaging a rotatable ring 67 arranged within a carrier or cam actuator casing 68. The casing has rods 69 extending therefrom, through openings in the cam 56, which are secured to the cam 61', and bearings 70 are arranged between the ring and the plate so that the ring can rotate 15 with the governor arms which bear thereagainst. Centrifugal force will move the weight members outwardly so that the arms will move the casing 68 and rods 69 forwardly against the tension of the spring 63 and as the cam 61' is secured to 20 the rods, it will also be moved axially to a position such that the lobes 61³ will be in position to actuate the rock levers 46 of the mechanisms operating the injection devices 26 and at the same time the lobes 61² will be clear from the 25 rock levers 46'. The spring tension can be arranged as desired so that a predetermined crank shaft rotation is required before the governor will shift the cam out of operative position with the injection devices 27 and into operative position with the injection devices 26.

The cam is positioned to actuate the devices 26 when the engine is running above idling speed, and is positioned to actuate the devices 27 when the engine is turning at idling or starting speed. 35 The cam lobes 61³ are arranged to actuate the rock levers 46 so that injection of fuel into the cylinders from the devices 26 will take place during the air compression strokes within a range between 40 and 20 degrees of the crank shaft 40 angle before top center is reached by the pistons. The cam lobes 61² are arranged to actuate the rock levers 46' so that injection of fuel into the cylinders from the devices 27 will take place about 5 degrees of the crank shaft angle before 45 the pistons reach top center during their air compression strokes.

The tension of the spring in the nozzle portion of the devices 26 is regulated to maintain a resistance to pressure so that proper atomization 50 of the fuel takes place, when the charges are of a quantity to cause the engine to perform work, and so that penetration of the compressed rotating air charges will result in commingling which will insure combustion by compression 55 without auxiliary ignition means. When the engine is idling the fuel charge is small and, consequently, the heat developed thereby is less than when the engine is running at higher speeds, furthermore the pump plungers are moved slower 60 when the engine is idling than when it is running under load so that the pressure developed behind the fuel charges with the devices 27 is not sufficient to penetrate the air charges to an extent causing the proper commingling to form 65 a mixture which will ignite under compression. Hence, starting and idling of the engine is uncertain with the devices 26 utilized as the injection means. By the provision of the devices 27, in which the tension of the nozzle springs 32 is 70 greater than that in the devices 26, a high degree of pressure behind the oil charges is obtained even though the pump plungers are retarded in their movement during injection strokes. This greater resistance to the nozzle 75

valves opening in the devices 27 will cause a pressure to be built up which will produce atomization and penetration of the air charges by the fuel oil sufficient to result in a mixture which will ignite under compression. The spring will hold the cam 61' into position to cause the devices 27 to be effective during starting and idling and the automatic mechanism will move the cam 61' into a position to cause the devices 26 to be effective when the R. P. M. of the engine exceeds idling speed.

While a specific embodiment of the invention has been described herein in detail, which is deemed to be new and advantageous and may be specifically claimed, it is to be understood that the invention is not limited to the exact details of the construction, as it will be apparent that changes may be made therein without departing from the spirit or scope of the invention.

20 What is claimed is:

1. In a compression-ignition engine, a cylinder, a pair of fuel injection devices opening into the cylinder and each comprising a plunger and a nozzle, said nozzles having spring pressed valves 25 opened under different pressures, and an actuating member selectively engageable with either of said devices.

2. In a compression-ignition engine, a cylinder, a pair of fuel injection devices opening into the 30 cylinder and each including a plunger and a nozzle, said nozzles having spring pressed valves opening under different pressures, means for feeding a common fuel oil to said pair of devices, mechanism associated with each injunction device to cause reciprocation of the plunger, an 35 axially shiftable cam member selectively engageable with either of said mechanisms, and resilient means associated to urge said cam member toward one extreme position of its axial movement.

3. In an internal combustion engine, a plurality of radially extending cylinders, a pair of fuel injection devices associated with each cylinder and communicating with the interior thereof, said devices each including a pump plunger and a nozzle having a spring pressed valve, the pressure required to open one of the valves for injection being different from that required to open the other valve, and shiftable engine driven 45 means selectively engageable with either of the plungers for actuating the same.

4. In an internal combustion engine, a plurality of radially extending cylinders, pairs of fuel injection devices connected with a common source 50 of oil supply and similarly associated with each of the cylinders and communicating with the interior thereof, said devices each including a pump and a nozzle having a spring pressed valve, the valves of each pair of nozzles being urged toward 55 closed position under different spring pressure, mechanisms for operating the plungers, the operating mechanism for the pumps in each pair being arranged in parallel planes, and a cam for actuating the pump operating mechanisms, said 60 cam being shiftable axially into the plane of either of the pump operating mechanisms.

5. In a compression-ignition engine, a cylinder, a pair of fuel injection devices opening into the cylinder and each including a plunger and 65 a nozzle having a spring controlled valve, one of said valves requiring a greater fuel pressure in the device than that in the other device before opening to allow fuel discharge thereby, a cam shiftable to actuate either of the plungers, means 70 responsive to engine speed for shifting the cam

in one direction, and a spring for shifting the cam in the other direction.

6. In a compression-ignition engine, a cylinder, a pair of fuel injection devices opening into the cylinder and each including a plunger and a nozzle having a spring controlled valve, one of the valves requiring greater fuel pressure than the other before opening, an engine driven cam, means normally positioning the cam to actuate the device requiring greater pressure to open the nozzle valve, and governor means responsive to a predetermined engine speed for positioning the cam in operative relation with the device requiring the lower pressure to allow fuel discharge past the nozzle valve. 15

7. In a compression-ignition engine, a cylinder, a pair of fuel injection devices opening into the cylinder and each including a plunger and a nozzle having a spring controlled valve, one of the valves requiring more fuel pressure than the other before opening, a shiftable engine driven cam, a spring normally positioning the cam to actuate the device requiring greater fuel pressure to open the nozzle valve, and governor means responsive to engine speed for moving the cam 20 against the spring tension into a position for actuating the device requiring the lower pressure to allow fuel discharge past the nozzle valve. 25

8. In a compression-ignition engine having a plurality of cylinders and a crank shaft, fuel 30 feeding means comprising two fuel injection devices associated with each cylinder for discharging fuel oil charges therein and each including a plunger and a nozzle, said nozzles having valves opening under different pressures, means 35 for feeding fuel oil of similar character to said devices, mechanisms extending into the crank case for operating the plungers, one of the mechanisms for each pair of devices being arranged in different planes axially of the engine, 40 a cam telescoping the crank shaft, means for rotating the cam at a reduced speed from the crank shaft, a governor fixed to the crank shaft having pivoted weights responsive to a predetermined speed, connections between the 45 cam and the pivoted governor elements for shifting the cam axially of the crank shaft to engage the forward operating mechanisms of the injection devices, and spring means urging said cam axially into position to engage the rear operating 50 mechanisms of the injection devices.

9. In an internal combustion engine, a crank case, cylinders extending radially from the crank case, a crank shaft extending axially of the crank case, a pair of spring controlled fuel oil injection 55 devices arranged to discharge into each of the cylinders and each including a plunger, one of said devices of each pair discharging in response to less pressure than the other, a mechanism for actuating each plunger, said mechanisms for operating each pair of devices being arranged in spaced relation axially of the crank case, an axially movable cam driven from the crank shaft, a governor secured to the crank shaft and including arms adapted to move axially, a ring engaged by the pivoted arms and connecting means including rods secured to the cam and casing with which the ring co-operates and moves axially to move the cam into a position for actuating the forward plunger operating mechanisms. 65

10. In a compression-ignition engine, a cylinder, a pair of injection devices associated to discharge fuel oil from a common source of supply into the cylinder and each including a plunger and a nozzle, said nozzles having valves opening 70

under different pressures, an operating mechanism associated with each plunger, said mechanisms being spaced, and an engine rotated cam member having two spaced sets of lobes each engageable with one of the mechanisms, said cam being shiftable axially to move either one of said sets of lobes to operative relation with one of the mechanism and moving the other of said sets of lobes out of operative relation with the other 10 of said mechanisms.

11. In an internal combustion engine having cylinders, a crank shaft and an air valve actuating cam driven at a reduced speed from the crank shaft, fuel injection mechanism comprising a pair 15 of devices each including a nozzle and a plunger associated with each cylinder, a mechanism for actuating each plunger, an axially movable cam keyed on the air valve actuating cam, said axially movable cam being adapted to be positioned to 20 actuate one of the plunger operating mechanisms of each pair, and shifting means connected with the axially movable cam.

12. In an internal combustion engine having cylinders, a crank shaft and an air valve actuating cam driven at a reduced speed from the crank shaft, fuel injection mechanism comprising a pair 25 of devices each including a nozzle and a plunger communicating with each cylinder, a mechanism for operating each plunger, an axially movable cam keyed on the air valve actuating cam for actuating either one of the plunger operating mechanisms, a spring urging the cam in one axial direction, and governor means including rods extending through the air valve cam connected 30 to the axially movable cam, said governor means having a portion fixed on the crank shaft and arranged to shift the rods connected to the movable cam axially in opposition to the spring upon 35 a predetermined shaft rotation.

40 13. In an internal combustion engine having

cylinders, a crank shaft and an air valve actuating cam driven at a reduced speed from the crank shaft, fuel injection mechanism comprising a pair of devices each including a nozzle and a plunger communicating with each cylinder, 5 mechanism for operating each plunger, an axially movable cam keyed on the air valve actuating cam, the axial position of said cam actuating either one or the other plunger operating mechanisms of each pair of devices, a spring engaging 10 the shiftable cam to urge it into one extreme position, and a governor means for moving the shiftable cam to the other extreme position, said means including weight members pivoted on the crank shaft, means fixed to the shiftable cam 15 and ball bearing means intermediate the weight members and the fixed means.

14. Fuel oil injecting means for the combustion chamber of an internal combustion engine comprising a pair of devices each including a 20 pump connected with a source of fuel and a nozzle having a spring closed outlet valve, said valves opening under different pump developed pressures relatively, a shiftable engine driven cam having two sets of lobes arranged to actuate the 25 pumps at different timing relatively, the later timed set of lobes being engageable with the pump of the device having the nozzle valve requiring the higher pressure for opening and the earlier timed set of lobes being engageable with 30 the pump of the other device, spring means normally maintaining said cam in position for the later time set of lobes to be effective, and speed responsive means associated with said cam to automatically move the earlier timed set of 35 lobes into effective position.
